UNITED STATES PATENT OFFICE.

WILLIAM T. GOLDSMITH, OF WASHINGTON, DISTRICT OF COLUMBIA.

BOTTLE-STOPPER AND DROPPER.

SPECIFICATION forming part of Letters Patent No. 766,688, dated August 2, 1904.

Application filed February 8, 1904. Serial No. 192,656. (No model.)

To all whom it may concern:

Be it known that I, WILLIAM T. GOLDSMITH, a citizen of the United States, residing at Washington, in the District of Columbia, have 5 invented certain new and useful Improvements in Bottle-Stoppers and Droppers; and I do declare the following to be a full, clear, and exact description of the invention, such as will enable others skilled in the art to which it app- 10 pertains to make and use the same.

This invention relates to combined bottle- stoppers and droppers.

The object of the invention is to provide a stopper which may be also used as a dropper 15 by which the contents of a bottle or other receptacle may be removed in drops.

A further object is to provide a device of this character which will be simple in construction, can be cheaply manufactured, and 20 is well adapted to the purposes for which it is designed, also providing a device of great convenience and usefulness which when used as a stopper is always at hand when required to be used as a dropper.

25 With these and other objects in view the invention consists of certain novel features of construction, combination, and arrangement of parts, as will be more fully described, and particularly pointed out in the appended 30 claims.

In the accompanying drawings, Figure 1 is a side elevation of a bottle, showing the device in use as a stopper. Fig. 2 is a similar view showing the device in use as a dropper. 35 Fig. 3 is a detail perspective view of the device removed from the bottle. Fig. 4 is a vertical sectional view of the same. Fig. 5 is a longitudinal section of a modified form of device. Fig. 6 is a vertical sectional view of 40 another modified form, showing in dotted lines the open position of the parts.

Referring more particularly to the drawings, 1 denotes a bottle, which may be of any style, having a neck 2.

45 3 denotes the stopper, which is in the form of a tapering plug and may be constructed of any suitable material. In Figs. 1 to 4 of the drawings the stopper is shown as being split or divided lengthwise to form a main body

portion 4 and a segmental strip 5, which when arranged in place next to the main portion forms therewith a conical-shaped or tapering plug. The two portions of the plug are pivotally connected together at their upper or larger end by means of a pin 6.

55 In the form of device shown in Fig. 5 the stopper is split or divided centrally, thus forming two counterpart sections *a* and *b*, pivotally connected together at their upper ends by a pin 6^a.

In the form of device shown in Fig. 6 the stopper is divided the same as in Fig. 5; but instead of being pivotally connected together, as in the other figures, they are hinged at their upper ends by means of a hinge 7, preferably 65 formed of a flexible strip, but which may be any form of hinge connection. The upper ends of the sections *a* *b* in this view are beveled upwardly from their outer sides to their inner engaging faces, as shown at 8, thereby 70 permitting one section of the same to be opened outwardly at a right angle to the other section, as shown in the dotted lines. In this form of stopper the meeting faces of the flat 75 engaging faces are slightly beveled or cut away at their inner ends, as shown at 9, to form finger-nail recesses to facilitate the separation of the two sections, as when used with some forms of liquid the sections might be caused to tightly adhere.

80 When in use as a stopper, the two sections are arranged together, as shown in Fig. 3, and the stopper forced into the neck of the bottle. In pressing the stopper in the sections are forced into air-tight engagement with each 85 other and the bottle securely closed.

When it is desired to use the stopper as a dropping device, the same is removed from the bottle and separated and one part only inserted in the neck of the bottle and slightly 90 tilted, as shown in Fig. 2. When in this position, the air passes into the bottle above the stopper-section and the liquid passes out below the same in the form of drops, as shown.

95 The flow of the liquid and the formation of drops may be controlled by inclining the bottle to a greater or less degree or by inserting the stopper-section more or less into the bot-

tle. In the case of very small-neck bottles the form of stopper shown in the first figures of the drawings is used, and for dropping from bottles of this kind the small section of the 5 stopper is used.

From the foregoing description, taken in connection with the accompanying drawings, the construction and operation of the invention will be readily understood without requiring a more extended explanation. 10

Various changes in the form, proportion, and the minor details of construction may be resorted to without departing from the principle or sacrificing any of the advantages of 15 this invention.

Having thus fully described my invention, what I claim, and desire to secure by Letters Patent, is—

1. A bottle-stopper comprising separable 20 longitudinal sections, substantially as and for the purpose described.

2. A bottle-stopper comprising separable longitudinal sections, and means for connecting the sections to permit them to be relatively 25 adjusted so that one of the sections alone may be placed within the neck of a bottle

for dropping purposes, substantially as described.

3. A bottle-stopper consisting of a tapering cylindrical body, divided lengthwise to form 30 two sections and joined at their upper ends to permit the sections to be separated, substantially as and for the purpose described.

4. A bottle-stopper consisting of a tapering cylindrical body, divided lengthwise to form 35 a large and a small segmental section pivotally connected together at their upper ends, substantially as described.

5. A bottle-stopper consisting of a tapering body longitudinally divided into sections 40 adapted to be separated, so that one section may be applied within the neck of a bottle to cause the contained liquid to discharge by drops when the bottle is tilted to a discharge position, substantially as described. 45

In testimony whereof I have hereunto set my hand in presence of two subscribing witnesses.

WILLIAM T. GOLDSMITH.
